UNITED STATES PATENT OFFICE.

ALFRED H. WILLETT, OF WEST NEW YORK, NEW JERSEY, ASSIGNOR TO AMERICAN ARCH COMPANY, OF NEW YORK, N. Y., A CORPORATION OF DELAWARE.

WOOTEN-FIRE-BOX ARCH.

1,229,386.

Specification of Letters Patent. Patented June 12, 1917.

Application filed February 11, 1916. Serial No. 77,643.

To all whom it may concern:

Be it known that I, ALFRED H. WILLETT, a citizen of the United States, and a resident of West New York, county of Hudson, 5 and State of New Jersey, have invented certain new and useful Improvements in and for Wooten-Fire-Box Arches, of which the following is a specification.

My invention relates to improvements in 10 locomotive boilers of the Wooten type which have firebox extensions within the barrel of the boiler forward of the grate.

The firebox of a Wooten type boiler differs from others chiefly in the matter of its 15 height. The distance between the grate and the crown sheet is much less than in locomotive fireboxes of other types. The reason of this peculiarity is that Wooten fireboxes are designed for use with anthracite coal; a 20 fuel which yields a very short flame, as compared with others, and which therefore necessitates the arrangement of the chief heating surface (the crown sheet) close to the fuel bed. The height of the firebox extension, sometimes called the "combustion 25 chamber extension", is determined by the height of the crown sheet, as in other fireboxes. Another characteristic of a Wooten firebox is that the grate is placed almost on 30 a level with the floor of the extension, and the throat sheet is extremely narrow.

It is claimed for the Wooten type firebox 35 that by reason of its low height and narrow throat sheet there is a substantially equal distribution of the hot gases in the flues of the boiler; and that this and the attendant easy maintenance of the flues and the flue sheet, are advantages secured without material loss of heating value in the walls of the 40 firebox, inasmuch as the latter are close to the fuel bed. Against the admitted advantages of such fireboxes, I find that the flow of hot gases from grate to flues is so rapid and direct that the rear part of a Wooten 45 firebox is much less effective than supposed.

It has been suggested that a cure may be effected by providing Wooten fireboxes with inclined refractory arches of the kind used in bituminous coal burning locomotives and 50 which in such locomotives have served to obviate disadvantages similar to those here mentioned as pertaining to Wooten fireboxes. But extensive experiments conducted in the past have made it appear that the lack of 55 height in the Wooten firebox, and its narrow

throat sheet, prevent the practical and efficient use of such arches. Wooten fireboxes of the extension-type are therefore customarily used without arches or baffle walls of any kind.

The object of my invention is to provide 60 within a Wooten type firebox a combination fire wall and arch which shall perform the same desirable functions as the arches which are used in bituminous coal-burning fire- 65 boxes.

The manner in which I attain this object, and the nature and particulars of my invention, will be understood on reference to the drawings that form part of this specification and in which:—Figure 1 is a transverse section on the line U—U of Fig. 2 of a Wooten-type firebox embodying my invention;—Fig. 2 is a longitudinal section on the line X—X of Fig. 1;—Fig. 3 is a sectional detail on the line Y—Y of Fig. 2;— 70 and Fig. 4 is a horizontal section on the irregular line Z—Z of Fig. 1.

The familiar parts of a Wooten type firebox are as follows:—The boiler-barrel, 2;— 75 the firebox shell, 3;—the mud ring, 4;—the side sheets, 5, 5;—the crown sheet, 6;—the rear sheet, 7;—side water legs, 8, 8;—the front water leg, 9;—the fuel door, 10;—and 80 throat sheet, 11;—the rear water leg, 12;— 85 the so-called fire-box extension, of which 13 is the floor;—the flue sheet, 14;—and, the flues, 15. The grate, 16, indicated by dotted lines, usually occupies the whole space within the confines of the mud ring, extending 90 from side to side of the firebox and from the rear sheet, 7, to the throat sheet, 11. The firebox-extension is all that part of the firebox between the flue sheet, 14, and the throat sheet. The throat sheet rises from the mud 95 ring to the crown sheet around the opening of the extension. The plate, 3', is the front plate or breast of the firebox shell, 3, which joins the shell, 2, of the boiler.

It will be noted that a Wooten firebox is 100 of much less height than width. Instead of attempting to employ a refractory arch extending upwardly and rearwardly from the lower part of the throat sheet, 11, I first divide the firebox into fire and combustion 105 chambers by means of a vertical wall, A, composed of refractory bricks, and positioned in the firebox-extension. I then construct an overhanging arch, B, rearwardly of the wall. My invention is chiefly con- 110

cerned with the means for supporting the overhanging arch.

The cross wall, A, may be of any desired construction. But I prefer that in all cases 5 it shall be provided with a clean-out opening, A', through which the combustion chamber may be reached. The overhanging arch, B, to be practical, must be composed of sectional arch bricks. Heretofore there has 10 been no practical way of supporting such bricks in the upper part of the wide firebox.

I overcome the many difficulties presented by using a plurality of longitudinally extending water circulating arch tubes some 15 of which (the middle group) rise from the floor, 13, of the firebox barrel or extension, while outer tubes extend rearward directly from those portions of the throat sheet which are at the sides of the extension. 20 Upon these arch tubes I arrange the refractory bricks which compose the body of the overhanging arch, B.

The arch tubes, C, D, and, E, are those which rise from the floor of the extension. 25 These tubes are curved upwardly and backwardly and pass through or over the wall, A, approximately half way of the height between the grate and the crown sheet. From that level the tubes slant upwardly, 30 and their ends are fastened in the upper part of the rear sheet, 7. These tubes, C, D, and, E, support two longitudinal rows, F and G, of arch component bricks, H.

The tubes, I and J, are the outer tubes 35 above referred to. These are secured in respective wings, 11', of the throat sheet, 11, at points far enough above the grate to allow ample fuel and fire clearance. It should be noted that the ends of the tubes, I and J, 40 are secured in the throat sheet at points far enough toward the outside to allow them to be reached through plugged openings, I', and, J', in the breast plate, 3', at the sides of the boiler shell, 2. Unless positioned in 45 this manner, the tubes, I and J, could not well be employed, for such tubes must be accessible from the exterior of the boiler; otherwise, they could not be secured in place and otherwise they could not easily be 50 cleaned.

From the points where they are fastened in the throat sheet the tubes, I and J, curve upward to the level of their straight portions and the straight portions of the three 55 tubes, C, D and E. The rear ends of the tubes, I and J, are fastened in the rear sheet, 7, and are accessible through normally plugged openings in the rear end of the firebox shell. The upwardly curved 60 front end, J^a, of the tube, J, clearly appears in Fig. 2.

My purpose in curving or bending the tubes, I and J, in this manner is to provide that difference in elevation between the front 65 and rear ends which is necessary to insure

the rapid circulation of water through the tubes from front to rear.

It will be clear that the front ends of the tubes, I and J, are below the corresponding parts of the middle tubes and therefore do not provide proper supports for arch bricks. Therefore upon the bend of each outer tube I place a leveling or saddle brick, K, the top, K', of which is substantially level with the tops of the tubes, C, D, and E, and in alignment with the tops of the straight portions of the tubes, I and J. The saddle bricks abut the throat sheet, 11. Their undersides are grooved to fit the tops of respective tubes. (See Fig. 3.)

The spaces between the tubes, I, and J, and respective side sheets, 5, are closed by marginal bricks, L, some of which rest upon the saddle bricks, K. The space between the tubes, I and E, and the space between 85 the tubes, C and J, may be closed by bricks, M, arched against one another, as shown in Figs. 1 and 3.

The forward bricks, M and H, preferably 90 abut the top of the wall, A.

It will be noted that in this construction all of the ends of the arch tubes are represented by plugged openings in the shell of the boiler. Hence all of the arch tubes are accessible from the exterior of the boiler, as 95 required, for easy installation and for cleaning the tubes.

The masses of fire brick positioned as shown in this Wooten firebox operate in the same manner as do the masses similarly arranged in bituminous-coal-burning fireboxes; and by means of the construction herein shown and described I make it possible to operate Wooten fireboxes with the same degree of economy, and secure there- 105 fore the same degree of protection for the seams and flues.

Having thus described my invention, I claim as new and desire to secure by Letters Patent:—

1. A locomotive boiler firebox having a barrel combustion chamber or extension and having a throat sheet which rises at the sides of said extension, in combination with inclined arch tubes which extend rearwardly 115 from the portions of said throat sheet at the sides of said extension, other arch tubes extending upwardly and rearwardly from the floor of said extension, a refractory cross wall in said extension and an arch 120 body composed of bricks supported by said tubes.

2. A locomotive boiler firebox having a barrel combustion chamber or extension and having a throat sheet at the sides of said ex- 125 tension, in combination with inclined arch-brick-supporting water-circulating tubes which extend rearwardly from said throat sheet at the sides of said extension, said tubes being curved upwardly adjacent said 130

throat sheet, saddle bricks fitted upon the curved portions of said tubes, a cross wall in said extension, and a refractory arch body which extends from one said tube and its 5 saddle brick to the other tube and saddle brick.

3. A locomotive boiler firebox having a barrel combustion chamber or extension and having a throat sheet which rises at the sides 10 of said extension, in combination with inclined arch supporting water circulating tubes which extend rearwardly from the portions of said throat sheet at the sides of said extension, said tubes being curved upwardly adjacent said throat sheet, saddle bricks conformed to and resting upon respective curved portions of said tubes, other 15

arch tubes extending upwardly and rearwardly from the floor of said extension, a refractory cross wall in said extension and 20 an arch body composed of bricks supported by all said tubes and said saddle bricks.

4. A locomotive boiler firebox having a barrel combustion chamber or extension and having a throat sheet which rises at the 25 sides of said extension, in combination with inclined arch tubes which extend rearwardly from the portions of said throat sheet at the sides of said extension, a refractory cross wall in said extension and a refractory arch 30 body having parts supported by said tubes.

In testimony whereof, I have hereunto set my hand this 1st day of February, 1916.

ALFRED H. WILLETT.
